US00D922279S

(12) **United States Design Patent** (10) **Patent No.:** **US D922,279 S**
Rekow (45) **Date of Patent:** **** Jun. 15, 2021**

(54) **CONTROL POD**

(71) Applicant: **Crown Equipment Corporation**, New Bremen, OH (US)

(72) Inventor: **Craig Rekow**, Troy, OH (US)

(73) Assignee: **Crown Equipment Corporation**, New Bremen, OH (US)

(**) Term: **15 Years**

(21) Appl. No.: **29/666,930**

(22) Filed: **Oct. 17, 2018**

(51) LOC (13) Cl. **12-16**

(52) U.S. Cl.

USPC **D12/174**

(58) **Field of Classification Search**

USPC D13/168; D21/333; D14/388; D12/174

CPC A63F 13/24

See application file for complete search history.

(57) **CLAIM**

The ornamental design for a control pod, as shown and described.

DESCRIPTION

FIG. 1 is a top, front, and side perspective view of a control pod shown in a use configuration with environment; FIG. 2 is a perspective view of the control pod as seen from the top, front, and first side;

FIG. 3 is a top plan view thereof;

FIG. 4 is a bottom plan view thereof;

FIG. 5 is a second side elevational view thereof;

FIG. 6 is a first side elevational view thereof;

FIG. 7 is a front elevational view thereof; and,

FIG. 8 is a rear elevational view thereof.

The broken lines shown in the drawings depict portions of the control pod that form no part of the claimed design. The broken lines in FIG. 1 depicting environment form no part of the claimed design. The dot-dash lines in the drawings depict boundaries and portions of the control pod that form no part of the claimed design.
